UNITED STATES PATENT OFFICE.

CILFTON ORICE MORGAN, OF YOUNGSTOWN, OHIO.

ELECTRICAL HEATING DEVICE FOR SMOOTHING AND DRYING HAIR ON A PERSON'S HEAD.

Application filed March 15, 1926. Serial No. 94,762.

This invention relates to beauty parlor devices, and more specifically to a device for evaporating moisture on a person's head; also a method of dressing hair.

One object of the invention is to provide a very convenient and effective device for quickly accomplishing the finishing step of the hair dressing method whereby extremely curly and rough hair can be made comparatively straight and smooth and caused to remain substantially in whatever arrangement it is fixed while the finishing steps of the method are being carried out.

Important features and objects will be pointed out or implied in the following details of the method and structure forming the invention.

In carrying out or performing the method, the hair is first moistened with oil, grease, water or other liquid or with a combination of these moistening agencies, and while thus moist, the hair is combed or brushed or otherwise arranged in the desired relation on the head. A cloth is then spread smoothly over the hair and secured firmly in position by any appropriate means, and then the heated drying device is pressed upon and slid over the cloth over the hair, while the hair is still damp, and the sliding movement is continued over all parts of the hair which it is desired to make smooth and comparatively straight, and when the heat from the device has made the hair comparatively dry, the cloth is removed and the hair remains substantially in the previously arranged relation, and relatively smooth and straight.

Forms and mechanical features of the invention are illustrated in the accompanying drawing, in which

Fig. 1 is a side view of the complete heating and drying device.

Figure 2 is an elevation viewed from the right side of Figure 1.

Figure 3 is a vertical sectional view in the plane indicated by line 3-3 of Figure 4.

Figure 4 is a substantially horizontal sectional view in the planes indicated by the line 4-4 of Figure 3.

By reference to these drawings in detail, in which similar reference characters correspond to similar parts in the several views, it will be seen that the device comprises a circular casing including two hollow casing members fitted one within the other and including upper and lower plates respectively.

On the upper plate is attached an electrical resistance wire coil 11 for generating heat which heats the lower plate of the inner hollow body. The outer hollow body or casing member 4 may be cast of iron or any appropriate kind of metal or alloy, and includes a circular horizontal plate 40 on which is attached a circular plate 5 of wood. This plate 5 and the upper plate or top of the casting 4 and an identification plate 6 are provided with openings through which screws 7 extend and are threaded into the plate 4, thereby securing these parts 4, 5 and 6 to one another. On each side of the device screws 1 extend through holes in plates 2 and in a strap 3, these screws being threaded in openings in the downwardly extending circular flange 4^A of the casing member 4, and hold the ends of the strap 3 against opposite sides of the flange 4^A.

Heat-insulating strip 8 fits closely around the inside of the flange 4^A and against an insulating plate 9. Metal clamps 10 extend over the resistance coil 11, through a mica plate 12, and are clinched over an insulating plate 13, and thus these members 10 hold these parts 11, 12 and 13 against one another, so they fit closely inside of the insulating strip 8 and rest against the insulating plate 9.

The casing member 4 has an opening in its downwardly extending flange 4^A, and a porcelain insulating member 14 extends through the said opening and has an enlarged collar at one end, also having two apertures through which extend two electrical conducting pins 15 which have diametral enlargements near their middle parts, which enlargements retain these pins in the desired position. A cap 16 is made of insulating material, has two apertures through which extend ends of conducting pins 15 and also openings for two screws 17, and there are two corresponding openings in flange 4^A into which is screwed these screws 17 and thus these screws 17 hold cap 16, pins 15 and insulating member 14 securely in the desired relation or position. An end of resistance coil 11 terminates and is secured to the inner end of one conducting pin 15, and the other end terminates at and is secured to the inner end of the other pin 15.

The outwardly projecting ends of pins 15 form a means for connecting the device to

an electrical current supplying source (not shown).

Member 18 is a circular sheet metal or alloy fitting, having an upwardly extending flange or rim 18^a, whereas its bottom plate is circular, concave and smooth and adapted to contact with a comparatively large area of the convex and other portions of a person's head, the hair on the head, or a cloth spread smoothly over the hair on a person's head. The hollow member 18—18^a fits closely inside of the heat insulating strip 8, and its flange 18^a, rests against insulating members 8 and 9 which latter is of asbestos. Screw 19 screws into an opening on one side of flange or rim 4^a, touches member 8, and by tightening this screw 19 it presses member 8 inward and thereby holds member 18—18^a firmly in the desired relation.

In using this device, it should be removed from the electrical current applying source when it has become sufficiently heated for drying the hair on a person's head and before it becomes hot enough to scorch the hair. Then the hand of the user is inserted through the loop of the strap 3 and by this means, the device is held in convenient relation for sliding the concave surface of the plate 18 over the cloth which is on the hair to be treated.

I have no intention of limiting the patent protection on this invention to the exact details of construction and arrangement here shown, but changes may be made within the scope of the inventive ideas as claimed in the following:

I claim:

1. In an electrical heating device for smoothing, drying and pressing hair on a person's head, the combination of a circular hollow casing member including an annular wall and having a plate closing its upper end, a heat insulating strip in said upper end, a heat insulating strip extending around

the inner surface of said casing member and 45 against the said heat insulating plate and under the margin of the latter, a second heat insulating plate under and against the first said heat insulating plate and having its periphery against the upper edge of said 50 heat insulating strip, an electrical heating coil provided with means securing it under the second said heat insulating plate, a heat insulating plate secured on the top of said casing member, a hand receiving loop 55 extending over the last said heat insulating plate, a sheet metal plate provided with a downwardly facing concave surface and with an upwardly extending flange, the latter fitting against the inner side of said heat insulating strip, the first said casing member having a threaded opening in its annular wall, and a screw in said threaded opening and operable to press the adjacent part of 60 said insulating strip inward and thereby exert a pressure against the flange of said sheet metal plate for frictionally holding the latter within said casing member.

2. The structure defined by claim 1, said casing member and insulating strip and sheet metal plate having corresponding openings therethrough, an apertured insulating member extending through these openings and assisting said screw in holding said insulating strip and sheet metal plate within said 70 casing member, electrical connecting members extending through said apertured insulating member and connected respectively to the terminals of said heating coil, and an apertured retaining member secured to said 75 casing member and being effective to secure said electrical connectors in said apertured insulating member and to secure the latter in said registering openings.

In testimony whereof, I hereunto affix my 80 signature.

CLIFTON ORICE MORGAN.
